UNITED STATES PATENT OFFICE

2,097,098

ELECTRIC SPATULA

Norman L. Hiscox, Lakewood, Ohio

Application December 6, 1934, Serial No. 756,198

2 Claims. (Cl. 219—21)

This invention relates to electrically heated spatulas.

One object of the invention is to provide an improved device of this character in which the heating element is arranged within the tool portion of the device and in close proximity to its free or operating point, whereby the latter is readily heated to and maintained at the desired temperature.

Another object of the invention is to provide an improved device of this character in which the heating element is arranged to be effective for heating the operating point of the tool while permitting the operator to hold the device relatively close thereto, whereby operation of the device is materially facilitated.

A further object of the invention is to provide an improved device of this character in which the heating means for the tool point is so arranged that heat guards and shields are eliminated.

A still further object of the invention is to provide an improved electrically heated spatula that is relatively simple in construction and may be readily and economically manufactured.

The invention is more fully described in the following specification, set forth in the appended claims and illustrated in the accompanying drawing in which is shown a longitudinal sectional view of the device.

The device herein shown comprises a handle 1 and a tool 2, detachably connected in end to end relation as hereinafter set forth. The tool 2 is formed of suitable conducting material having high heat conductivity. The handle 1 is formed of suitable non-conducting material, such as bakelite, and is preferably hollow from end to end to facilitate manufacture and assembly of the parts and to enclose leads 11, 11a. The leads 11, 11a, are electrically connected to suitable contacts 12, 12a, mounted on the inner wall of the handle 1 adjacent its rear end, these contacts providing for the connection of the lead-in wires 14, 14a, which are preferably connected into a single strand 5, and supply current from a suitable step-down transformer (not shown). The rear end of the handle 1 is closed by a suitable tip 4 preferably threaded into the end thereof. The lead 11a extends through the handle 1 and at its forward end is suitably connected to a threaded collar 9 formed of copper or other conducting material. The collar 9 is arranged at the forward end of the handle 1 and removably receives an externally threaded member 15 integrally connected to and projecting from the rear or for-

ward end of the tool 2. The forward end of the lead 11a and collar 9 are secured in position by a screw 18 extending through the side wall of the handle 1 and preferably countersunk therein.

The lead 11 also extends through the handle 1 but terminates at a point remote from the end of the handle 1 and preferably serves as one member of a switch (to be later referred to) for which reason the lead is resilient so that its inner end normally tends to swing outwardly. The forward end portion of the handle 1 is formed with an opening 1a in which is slidably mounted a button 3 of non-conducting material, the button being normally pressed outwardly by the lead 11 and adapted to be engaged by the finger of the user and pressed inwardly to close the switch. The button is provided on its inner end with a head to limit its outward movement.

The tool 2 comprises a body portion 2a and an extension 2b terminating in a spatula point 2', the body portion and extension being preferably formed integral. The body portion 2a and member 15 are formed with an opening 2c extending inwardly from the inner end of the latter axially of the tool 2 for a purpose later set forth. 7 25 indicates a suitable heating element preferably comprising a coil of nichrome resistance wire embedded in suitable cement 6 within the opening 2c, the cement being capable of withstanding the heat generated in the wire 7. The cement fills 30 the opening 2c and the space within the member 15. One end of the coil 7 is extended outwardly and soldered to the outer end of the member 15, so that one side of the circuit is from the lead 11a, through the collar or cylinder 9, member 15 35 to one end of the coil.

The other end of the coil 7 is soldered or otherwise connected to the inner end of a conductor, preferably comprising a rod 8, having a portion embedded in the cement 6 and extending axially 40 outwardly through the member 15 and therebeyond for engagement by the movable end of the lead 11. 19 indicates an annulus formed of insulating material and surrounding the conductor 8 and insulating it from the member 15 and closing 45 the outer end of the member 15, the cement serving to hold the annulus in position. The cement when inserted in the opening 2c is in a liquid state and permits the coil 7 and rod 8 to be readily inserted before setting.

From the foregoing description it will be noted that the heating means is within a portion of the tool, the control switch is arranged at the forward end of the handle and the handle being formed of non-conducting material, the user 55

may hold the device close to the spatula point to conveniently and accurately operate it and at the same time he may with the same hand control the heating thereof without changing the position of the tool or stopping his operations.

To those skilled in the art to which my invention relates, many changes in construction and widely differing embodiments and applications of the invention will suggest themselves without departing from the spirit and scope of the invention. My disclosures and the description herein are purely illustrative and not intended to be in any sense limiting.

What I claim is:—

15 1. A spatula instrument comprising an insulating hollow handle into which lead conducting wires, characterized by a tool piece formed of conducting material adapted to be mounted on one end of the handle, such tool piece formed to have a working end to be heated by electricity supplied through the said wires, and a body portion to the rear of said working end and integral therewith which is made hollow to form a socket, a heating coil located in said socket, a body of insulating material filling the socket and embedding the heating coil therein, and a conducting pin also insulated by the said body of material and extending therefrom into the handle, one end of the coil being electrically connected to the said pin and through it adapted to have electric connection with one of the lead-in wires, and the other end of the coil arranged

to have electric connection with the other lead-in wire, the flow of current through the coil being controlled by a switch.

2. A spatula instrument comprising in combination an insulated hollow handle into which lead conducting wires, a threaded collar formed of conducting material fitted into the front end of the handle, a tool piece made of conducting material and formed to have a working end that is heated by electricity furnished through the wires in the handle, a body portion to the rear of said working end that is made hollow to form a socket and an externally screw-threaded projection to the rear of the body portion adapted to engage with the collar and thus unite the tool piece to the handle, the socket in the body of the tool piece extending through the said projection, a heating coil located in the socket in the tool piece, a body of insulating material filling the socket and embedding the heating coil therein, and a conducting pin also insulated by the said body of material and extending through the opening in the threaded projection of the tool piece, one end of the coil being electrically connected with the tool piece and the other end with the said pin, the wires leading into the handle being arranged to be connected one with the screw-threaded collar and the other to have connection with the pin whereby current may be furnished to the coil to cause the same to be heated.

NORMAN L. HISCOX.
